UNITED STATES PATENT OFFICE.

GRANT SIPP, OF PATERSON, NEW JERSEY.

REED STRUCTURE.

Application filed December 6, 1924. Serial No. 754,248.

To all whom it may concern:

Be it known that I, GRANT SIPP, a citizen of the United States, residing at Paterson, in the county of Passaic and State of New Jersey, have invented certain new and useful Improvements in Reed Structures, of which the following is a specification.

This invention relates to reeds used in controlling warp threads. Certain reeds of this class, as those used in warp creels, include glass bars as their dents and when these break or become worn it is frequently difficult to remove and replace them with new ones because the frame in which they are mounted has solid top and bottom bars simply drilled to receive them. For example, if a fragment of a broken dent is left in the hole drilled in the lower bar to receive the dent the same cannot be removed without resort to some makeshift, as an adhesive applied to a thin stick and used to lift out the broken piece. One object of this invention is to provide a reed frame from which any dent may be readily removed and which will be quite strong and durable, though light in construction and inexpensive to manufacture. Another object is to provide for the support of a reed frame in the creel, or other structure in which it is mounted, so that it will be readily capable of up-and-down adjustment and yet securely stayed, although the reed may be quite long and hence limber and pitched at an incline.

In the drawings,

Fig. 1 is a front elevation of the upper part of a creel embodying my invention;

Fig. 2 is a front elevation, partly broken away, of the reed;

Fig. 3 is an end view; and Fig. 3^a a fragmentary plan of the reed;

Fig. 4 is an enlarged front elevation of what appears in Fig. 1;

Fig. 5 is a side elevation thereof; and

Fig. 6 and 7 are sectional views on lines 6—6 of Fig. 4 and 7—7 of Fig. 1.

Referring first to Figs. 1 to 3^a: *a* and *b* designate the top and bottom bars of the reed frame, these being formed longitudinally channeled. The sides and bottom of the channel respectively produce the front and rear sides and bottom of the top bar *a*; the sides and bottom of the channel respectively produce the top and bottom and rear sides of the bar *b*. These bars are connected at suitable intervals so as to make a rigid frame structure as follows: *c* designates one of several posts which penetrate suitable holes in the upper side or wall of the lower bar and abut at their ends the bottom wall or side of the upper bar and the bottom wall or side of the lower bar, being secured to the two bars by screws *d* extending through holes in the bars and tapped into the ends of the posts. Since the holes through which the posts extend in the upper wall of the bar *b* fairly snugly fit the posts the reed frame has an element of rigidity and strength which it would not otherwise have. *e* designates the glass bars, and these are received by aligned perforations or other openings *f* in the bottom wall of the top bar and the top wall of the lower bar, having underneath support on the lower wall of the lower bar. There is a removable plate *g* secured on the upper bar by screws *h* and forming a cover for its channel, and when this is removed any dent may be readily withdrawn and a fresh one inserted; if a dent breaks the fragment can be readily removed from the lower bar because it is channeled and its channel opens laterally.

To the horizontal rail *i* of a suitable supporting structure, as the creel shown in Figs. 4 to 7, a pair of upright guides *j* are secured, these having vertical channels facing each other and forming guideways for the ends of the reed. These guideways are usually pitched to more or less of an incline, so that the reed stands correspondingly pitched, and if the reed is very long and consequently tends to bow under the weight of itself and the warp it is desirable to support it as nearly true to a plane as possible. Further, it is generally necessary to provide for adjusting the reed to different heights. I therefore provide means to receive and support the lower part of the reed as follows: At each of suitable intervals lengthwise of the rail *i* there is secured thereto a bracket *k* (Figs. 1, 4 and 6) which receives the lower bar of the reed and whose legs or sides are parallel and spaced sufficiently to fairly snugly receive the bar and form a guide therefor. Into each bracket from beneath is tapped a set-screw *l*, which may have a lock nut *m*. Each set-screw supports the reed and by adjusting the several set-screws the reed can be brought to the proper height and leveled up, and in any position of adjustment it is stayed against forward or back bowing or appreciable displacement by the brackets *k*. If the reed is very long it

is supported by brackets *k* at intervals along the rail *i*. The rail *i* is supported by a suitable structure, as shown in Figs. 4 to 7, which includes a pair of upright guides *j* secured to the rail *i* and having vertical channels facing each other and forming guideways for the ends of the reed. These guideways are usually pitched to more or less of an incline, so that the reed stands correspondingly pitched, and if the reed is very long and consequently tends to bow under the weight of itself and the warp it is desirable to support it as nearly true to a plane as possible. Further, it is generally necessary to provide for adjusting the reed to different heights. I therefore provide means to receive and support the lower part of the reed as follows: At each of suitable intervals lengthwise of the rail *i* there is secured thereto a bracket *k* (Figs. 1, 4 and 6) which receives the lower bar of the reed and whose legs or sides are parallel and spaced sufficiently to fairly snugly receive the bar and form a guide therefor. Into each bracket from beneath is tapped a set-screw *l*, which may have a lock nut *m*. Each set-screw supports the reed and by adjusting the several set-screws the reed can be brought to the proper height and leveled up, and in any position of adjustment it is stayed against forward or back bowing or appreciable displacement by the brackets *k*. If the reed is very long it

will be desirable to stay it at a higher elevation than is afforded by the brackets *k*, and for that purpose I provide a brace *n* consisting of a strip which is secured to the rail *i* and has its free end bent forward as shown in Fig. 7 and penetrated by one of the posts.

Having thus fully described my invention, what I claim is:

1. A reed frame including spaced top and bottom horizontal bars and means to connect them, the upper bar having openings to receive the reed dents and the lower bar being channeled lengthwise and having the sides of its channel forming the top and bottom of the bar and the relatively upper side having openings to receive the dents and the lower side forming an underneath support for the dents.

2. A reed frame including spaced top and bottom horizontal bars and means to connect them, the lower bar having openings to receive and also affording an underneath support to the dents and the upper bar being channeled lengthwise and having the sides of its channel forming the front and back, and the bottom of its channel the bottom, of the bar, and the bottom of the bar having openings to receive the dents.

3. A reed frame including spaced top and bottom lengthwise - channeled horizontal bars, the lower bar having the sides of its

channel forming the top and bottom of the bar, and posts extending through the relatively upper side of the lower bar and abutting at their upper ends the upper bar and secured thereto and at their lower ends abutting the relatively lower side of the lower bar and secured thereto, said bars having openings to receive the dents and the lower bar affording underneath support to the dents.

4. In combination, a supporting structure, a horizontally extending reed arranged and movable in an upright plane, said structure having upright guideways receiving the end portions of the reed, U-shaped brackets secured to said structure and receiving the lower edge portion of the reed between its ends and supporting the reed between said ends against forward and back displacement, and an adjusting screw arranged in each bracket and supporting the reed.

5. In combination, a supporting structure, a horizontally extending reed arranged and movable therein in an upright plane and including top and bottom horizontal bars and a post rigidly connecting them, and a brace extending from said structure and penetrated by and having the post slidably therein.

In testimony whereof I affix my signature.

GRANT SIPP.
